INVENTOR

UNITED STATES PATENT OFFICE.

CAMDEN RILEY, OF SALT LAKE CITY, UTAH.

RAILWAY CATTLE-GUARD.

1,287,752.

Specification of Letters Patent. Patented Dec. 17, 1918.

Application filed April 16, 1918. Serial No. 228,967.

To all whom it may concern:

Be it known that I, CAMDEN RILEY, a citizen of the United States, residing at Salt Lake City, Salt Lake county, State of Utah, have invented a new and useful Improvement in Railway Cattle-Guards, of which the following is a specification.

The objects of this invention are to prevent cattle from trespassing upon railway road beds, and to reduce the danger from fire on trestles, culverts and bridges.

I attain these objects by the device illustrated in the accompanying drawings, in which:

15 Figure 1 represents the cattle guard disconnected from the road bed.

Fig. 2 represents the cattle guard as it appears when in place in the road bed, Fig. 3 represents a cross section of Fig. 1 taken on 20 the line A—B, and Fig. 4 an end view.

The invention consists of several of the metallic beams, 1 which are so constructed that their upper parts are cut and bent to form the guards, 2 which are arranged and 25 bent alternately inwardly and outwardly at a slanting angle from the level of the road bed, the points being preferably turned slightly upward, and are so arranged that each guard points to the open space between 30 the inwardly pointing guards on the opposite side of the beam as shown in Fig. 2.

These guards may be painted in various colors, preferably in red, white and black alternately as cattle have an antipathy for 35 alternating colors.

Adjustable rail seats, 3 are placed in each end of the channels of the beams, 1 for the purpose of supporting the rails which are fastened to these rail seats as shown in Fig. 2.

40 These adjustable rail seats have notches, 4 cut in their upper edges. Into these notches are placed the bands, 5 which pass over these rail seats, 3 and downward through holes in the sides of the beams, 1.

45 The bands, 5 secure the rail seats, 3 in the channel of the beams, 1 as shown in Fig. 2, and are so made at each end that they may be loosened or tightened as the expansion or the contraction of the beams or of the rail

seats may require as a result of weather or 50 other conditions.

To securely anchor the beams, 1 in the road bed and to prevent their moving longitudinally in the road bed, the anchors, 6 project downward from the bottom of the 55 channels of the beams into the road bed near each end of the beams.

To prevent the beams, 1 from buckling, and to give them additional strength, and to hold the ballast in place the sides of the 60 beams extend downward and below the bottom of the channels of the beams as shown at 7.

To allow for drainage holes are made in the bottom of the beams, 1 at intervals along 65 their length.

The guard as constructed is practically immune from fire.

Having thus described my invention I desire to secure by Letters Patent and claim: 70

1. A railway cattle guard composed of trough shaped metallic beams having sides extending downward and below the bottom of the channel of the beams, the bottom of the channel being formed by turning the 75 metal at a right angle to the perpendicular sides of the beams at a point above the bottom of the perpendicular sides of the beams.

2. A railway cattle guard composed of metallic beams having alternating guards 80 projecting from the tops of the perpendicular sides of the beams; having sides extending downward and below the bottom of the channel of the beams, the bottom of the channel being formed by turning the metal 85 at a right angle to the perpendicular sides of the beams at a point above the bottom of the perpendicular sides of the beams; anchors projecting downward from the bottom of the channel of the beams into the road 90 bed; and means for drainage.

3. A railway cattle guard composed of metallic beams having colored, alternating guards projecting from the tops of the perpendicular sides of the beams; having sides 95 extending downward and below the bottom of the channel of the beams, the bottom of the channel being formed by turning the

metal at a right angle to the perpendicular sides of the beams at a point above the bottom of the perpendicular sides of the beams; anchors projecting downward from the bottom of the channel of the beams into the road bed; means for drainage; rail seats secured and adjusted by adjusting bands passing over their top, fitting into

notches in their upper edges, and passing downward through holes in the sides of the beams; and adjusting bands passing over the rail seats, fitting into notches in their upper edges, and passing downward through holes in the sides of the beams. 10

CAMDEN RILEY.
